CONVERTIBLE MOTOR BICYCLE

William R. Maijala, 4029 Xenia Ave. N.,
Minneapolis, Minn. 55422

Continuation-in-part of abandoned design application Ser.
No. 22,048, Mar. 25, 1970. This application Mar. 29,
1971, Ser. No. 129,287

Term of patent 14 years

Int. Cl. D12—13

U.S. Cl. D14—24

Fig. 1

Fig. 2

FIG. 3

FIG. 4

FIG. 1 is a right side elevation of a convertible motor bicycle showing my new design;

FIG. 2 is a top plan view thereof;

FIG. 3 is a front elevation thereof; and

FIG. 4 is a rear elevation thereof.

The side opposite to that shown in FIG. 1 is a mirror image thereof.

This application is a continuation-in-part of my copending application Ser. No. D. 22,048, filed Mar. 25, 1970, now abandoned.

I claim:

The ornamental design for a convertible motor bicycle, as shown and described.
